COMBINED PACKAGE AND SPREADER FOR PULVERULENT MATERIAL

William E. Beaumont, Marina del Rey, Calif., assignor to
Downey Fertilizer Company, Downey, Calif., a corpora-
tion of California

Filed Apr. 24, 1968, Ser. No. 11,593

Term of patent 14 years

Int. Cl. D9—04; D8—01

U.S. Cl. D9—221

FIG. 1 is a front perspective view of a combined package and spreader for pulverulent material showing my new design;

FIG. 2 is a rear elevation thereof on an enlarged scale;

FIG. 3 is a side elevation thereof, the side opposite being identical;

FIG. 4 is a bottom plan view thereof;

FIG. 5 is a top plan view thereof; and

FIG. 6 is a fragmentary front elevation showing an embodiment of my new design wherein the edges of the handle are beveled.

The bottom part of the design shown in FIG. 6 is identical to that shown in FIGS. 1-5.

I claim:

The ornamental design for a combined package and spreader for pulverulent material, substantially as shown and described.
